UNITED STATES PATENT OFFICE

HENRY UNDERBERG, OF BROOKLYN, NEW YORK, ASSIGNOR TO FRANKART, INC., OF NEW YORK, N. Y., A CORPORATION OF NEW YORK

DESIGN FOR A STATUETTE OR SIMILAR ARTICLE

Application filed September 3, 1931. Serial No. 41,006. Term of patent 3½ years.

To all whom it may concern:

Be it known that HENRY UNDERBERG, a citizen of the United States and resident of Brooklyn, in the county of Kings and State of New York, has invented a new, original, and ornamental Design for a Statuette or Similar Article, of which the following is a specification, reference being had to the accompanying drawing, forming part thereof, in which the figure is a perspective view of a statuette embodying my new design.

The statuette may be used for book ends and the like ornamental articles.

I claim:

The ornamental design for a statuette or similar article, substantially as shown and described.

Dated, August 31, 1931.

HENRY UNDERBERG.
